UNITED STATES PATENT OFFICE.

RALPH C. LEWIS, OF BOSTON, MASSACHUSETTS.

DESIGN FOR AN AUTOMOBILE-FRONT CASING.

No. 38,108.

Specification for Design.

Patented June 26, 1906.

Application filed September 5, 1905. Serial No. 277,112. Term of patent 3½ years.

To all whom it may concern:

Be it known that I, RALPH C. LEWIS, a citizen of the United States, residing at Boston, in the county of Suffolk and State of Massachusetts, have invented a new, original, and ornamental Design for Automobile - Front Casings, of which the following is a specification.

Figure 1 is a perspective view of an auto-

mobile-front casing, showing my new design. Fig. 2 is a front elevation of the same.

I claim—

The ornamental design for an automobile-front casing, as shown.

RALPH C. LEWIS.
